UNITED STATES PATENT OFFICE.

JOHAN NICOLAAS ADOLF SAUER, OF AMSTERDAM, NETHERLANDS.

APPARATUS FOR DRYING, BURNING, AND RECOVERING FINELY-DIVIDED MATERIALS.

Application filed May 26, 1923. Serial No. 641,775.

To all whom it may concern:

Be it known that I, JOHAN NICOLAAS ADOLF SAUER, residing at Amsterdam, Netherlands, have invented certain new and 5 useful Improvements in and Relating to an Apparatus for Drying, Burning, and Recovering Finely-Divided Materials, of which the following is a specification.

The invention is an improvement in the 10 apparatus for the revivifying or "burning" of finely powdered adsorbent materials, e. g. decolorizing carbon, kieselguhr, fuller's earth and the like.

Experiments have shown that for the 15 regular, uninterrupted and efficient operation of the apparatus, it is of greatest importance, in the revivification by heat of finely powdered materials such as decolorizing carbon, to arrange for quick and 20 regular, and preferably uninterrupted removal of the evolved gases and vapors which are formed by the drying and burning of the mass.

In order to obtain a quick removal of the 25 evolved gases and rapid condensation with prevention of obstruction, it has been found to be necessary that the condensation and dust collecting device should consist of a plurality of units, each unit being arranged 30 adjacent or connected to, one end of the heating or "burning" cylinders and in proximity thereto, and connected therewith by short and preferably wide conduits, preferably not exposed to direct heat such 35 as flue gases, but arranged for example outside the brickwork of the furnace and which short conduits can be cleaned from the outside.

A further characteristic, to allow of uninterrupted operation of the furnace, is the 40 provision of more than one tank placed near and connected to the receiving tank for the heated or burned material leaving the last retort. The first tank may thus 45 be water sealed and the entrance of air into the first (receiving) tank thus prevented.

Moreover the quantity of evolved gases in the retort must be as small as possible, as it is these evolved gases which carry 50 along the fine particles of the product, and tend to obstruct the outlets so as to prevent the production of a highly active mass, as in such case the decomposed tarry distillation products are not sufficiently removed.

This requires gradual drying of the material before same is exposed to high temperatures.

The improved apparatus is designed with the following objects in view:

To reduce to a minimum the quantity of 60 evolved gases or vapors in the cylinders or retorts.

To construct the apparatus in such way, that the conduits leading from the cylinders to the condensation device are as wide 65 and short as possible.

To provide for these connecting conduits being easily cleaned from the outside.

To allow of easy removal of the recovered material and of the condensation products from the condensation device.

To allow of an uninterrupted operation of the apparatus.

With the object of obtaining the above mentioned advantages, a pre-drying conveyor with a mechanical propelling device is used, in which the wet material to be "burned" is first pre-dried, but preferably without proceeding to such a degree of dryness as to cause the product to enter the 80 retorts in a perfectly dry state, as otherwise there would be excessive production of dust and consequent loss.

Pre-drying tanks or other suitable devices may be used for the pre-drying, and 85 these may be in combination with the above mentioned pre-drying conveyor.

Furthermore there is preferably a plurality of, or at least two condensation devices, which may for example be placed at both 90 ends of the retorts or cylinders so that the connection to the retorts is as short as possible.

The vents for the gases from the retorts are arranged at a part outside the zone 95 where the heat or the hot gases surround the retorts, e. g. outside the brickwork of the furnace, where in the case of a plurality of cylinders the unions between the same are arranged.

Furthermore the device allows of removing a large quantity of the condensable gases beforehand at a low temperature, so that the evolving of gases in the retorts proper is limited to those products of decomposition which are formed at a higher temperature.

The invention will now be described more

fully with reference to the accompanying drawings, which illustrate one form of a construction embodying the improvements.

Fig. 1 is a front elevation of the apparatus, with parts broken away.

Fig. 2 a top plan view.

Fig. 3 a side elevation seen from the right of Fig. 1.

Fig. 4 a side elevation seen from the left of Fig. 1.

Gases and vapors evolved by the drying and "burning" of the wet material may escape from: (1) the pre-drying conveyer 1, (2) the upper retort 2, (3) the lower retort 3, through wide tubes 5, 6, 7, and 8 connected to the retorts and to the vertical condensers 9 and 10. 1, 2 and 3 are provided with suitable means for feeding the material through them. The drawing showing this in the form of conventional feeding screws, illustrated in Fig. 1.

A plurality of retorts and a plurality of pre-drying conveyers as well as a plurality of condensation devices may of course be used, in case the apparatus is to be of a large capacity. The condensers may be filled with a quantity of water up to the overflows 17 and 18. In the condensers a draft is produced by means of the chimneys 11 and 12.

Each condenser is divided vertically, to within a short distance above the liquid level by means of a vertical partition 2. Escaping gases and light particles enter the condensers through the tubes 5, 6, 7, 8. The water vapor is condensed in the condenser by cooling by means of air or water, and the solid particles of dust are carried down by the condensation products (water) and collected in the water at the bottom of the condenser.

The uncondensable gases are carried away through the chimneys 11 and 12.

According as the moisture content of the material to be revivified is higher or lower, the deposits in the condensers will be of a more or less solid nature.

If the moisture content is too low, then cakes will be formed in the upper parts of the condensers in consequence of the adhering properties of the finely powdered material, especially carbon. The escape of the gases may thus be prevented. For this reason finely divided water or steam is injected into the upper part of the condenser through sprayers (atomizers) 14, in case rather dry carbon is to be treated, and this will prevent the particles of carbon from caking together. The spraying may be regulated by means of valves 15, 16. The surplus of condensable products and water is drained off automatically by the overflows 17, 18, and these also keep the water in the condensers at the same level.

The condensers are emptied once or twice daily, in order to recover the carbon con-

tained therein. This carbon will have formed a deposit on the bottom of the condensers. By means of compressed air from the pipe line 19, 20 the water in the condensers is mixed with the carbon and this mixture, rendered sufficiently liquid, may be carried away by means of an injector 21 or a pump.

As the overflows 17, 18 are fitted with a siphon, no air can enter the condensers, as the lower part of the siphon is always filled with water.

22, 23, are water supply cocks.

24, 25 are test cocks.

In order to allow of uninterrupted operation of the furnace a second tank 27 is placed beside the receiving tank 26. Tank 26 may be closed hermetically by a cover 28 and a stuffing box 29 placed around the mixing shaft 30. Mixing arms 31 keep the contents in motion to prevent the settling of solid particles.

From the lower part of the tank 26 a connecting pipe 32 with a valve 33 connects with the outlet of tank 27. Tank 27 also has a mixing shaft 34 and mixing arms 35, but is open at the top. The level and the density of the liquid in both tanks may be ascertained by looking in tank 27. The valve 33 is only used in case one of the tanks is to be cleaned or repaired.

The suction pipe 36 and valve 37 of the pump are connected to tank 27, the connecting being made in such a way that a certain quantity of water will remain in said tank after pumping the deposit away. This prevents the entrance of air into tank 26. The emptying of the both tanks can be effected through outlet 38 and valve 39 fitted to the bottom of tank 26. Valve 33 remains opened and valve 39 closed while pumping the carbon paste away under normal conditions. When both tanks are emptied only valves 33 and 39 are opened.

The water vapor in tank 26, formed by the falling of the hot material into the water is sucked away through pipe 40, which also is connected with the condenser 9.

The greater part of the water vapor formed in the pre-drying conveyer, is by the device according to this improved system directly removed and does not enter the retorts, consequently cannot cause the carrying off of large quantities of fine particles of the material.

The whole device is compact and practical and does away with the necessity for continuous cleaning of the connecting conduits which carry away the gases.

The pre-drying conveyer trough is closed and has two closable openings, one at the part where the material is fed into the trough and one at the part where the trough is connected with the upper retort.

By using an ascending connection between

the pre-drying trough and the condenser a regular removal of the vapors is obtained.

The ends of the retorts 2 and 3 extend outside the brickwork into proximity with the two condensation devices 9 and 10.

The condenser 10 is provided with connections 5 and 6 from the retorts, having short T tubes 42, each closed by a removable plate 43.

10 The other condenser is also provided with connections 7, 8, from the retorts 2 and 3 respectively.

What I claim is:

Apparatus for the continuous drying and heating of finely divided material and especially suitable for revivifying spent de-colorizing carbon, kieselguhr, fuller's earth and the like adsorbents, comprising a plurality of drying and "burning" retorts, mechanical means for moving solid material through said retorts, and condensation and dust collecting apparatus, which condensa-

tion and dust collecting apparatus is composed of a plurality of units, each of which is independently connected with the said retorts by short wide conduits not directly exposed to the heating medium, which conduits are capable of being cleaned from the outside, said condensing apparatus being provided with at least two receiving tanks 25 for the solid material recovered in said condensing apparatus, said tanks communicating with each other, one of said tanks being closed by a water seal and serving for directly receiving said solid material, said 30 other tank being provided with means for removing the treated material.

In testimony whereof I affix my signature in presence of two witnesses.

JOHAN NICOLAAS ADOLF SAUER.
